T. R. E. RUNDQVIST

DRILLING MECHANISM

Filed March 13, 1924

UNITED STATES PATENT OFFICE.

THORE R. E. RUNDQVIST, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed March 13, 1924. Serial No. 699,111.

This invention relates to drilling mechanisms.

It has for its object to provide an improved drilling mechanism. A further object is to provide a drilling mechanism having an improved feeding means with improved means for controlling the flow of fluid to the feeding mechanism. A further object is to provide improved feed control means particularly adapted for a "spotting" operation. It is a further object to provide an improved feed control mechanism that will automatically hold the drilling mechanism in substantially a stationary or balanced condition. It is a further object of my invention to provide such a controlling means for the feeding mechanism which employs a piston having differential areas so that the forward feeding force will be just sufficient to hold the steel in a spotting position against the recoil of the drilling motor.

In the accompanying drawings I have shown for purposes of illustration one form which my invention may assume in practice.

In these drawings,—

Fig. 1 is a side elevation partially broken away to show details of construction.

Fig. 2 is a diagrammatic view of my improved control means for substantially balancing the feed.

Fig. 3 is a transverse vertical sectional view taken substantially on line 3—3 of Fig. 1.

Fig. 4 is a detail sectional view of the valve 30 shown in Fig. 2 with the valve in a different position.

Fig. 5 is a detail sectional view of the control valve 10 illustrating the connection of the forward and reverse feeding passages.

In the illustrative form of my invention it is shown as embodied in a drifter type of drill comprising a combined feed cylinder and support 1 having a depending member 2 adapted to be engaged by any suitable support and having longitudinal guideways 3 disposed on the upper side thereof within which is slidably mounted a drilling mechanism 4. This mechanism comprises a usual percussive motor cylinder 6 having a chuck 7 mounted thereon and adapted to carry a steel 8 while a rear cylinder head 9 carries a usual pressure fluid control valve 10

having communication with a main fluid passage 11 leading to a fluid distribution valve 12 for the motor 6.

The feeding mechanism of my improved device comprises an arm 13 projecting rearwardly from the lower side of the head 9 and terminating in depending members 14 and 15 which carry at their lower end a boss 16 having a conical bore 17 within which a plug 18 is disposed and held therein by a nut 19. Threadedly connected to a reduced portion 20 of the plug 18 is a hollow piston rod 21 projecting forwardly through a combined rear cylinder head and packing member 22. Mounted upon the forward end of the rod 21 is a piston 23 held thereto as by a hollow nut 24. Also carried by the member 18 is a fluid conducting tube 26 which projects forwardly from a chamber 27 and terminates in a head 28 adjacent the nut 24.

In order that the drilling mechanism 4 may be held to its spotting position independently of the main control valve 10, I have provided the following mechanism comprising a balancing valve 29 controlled by a manual valve 30. The object of the balancing valve is to substantially equalize the rearward and forward feeding forces so that the feeding mechanism may, according to the proportions given my balancing valve, either be held in a complete balanced condition or given a slight forward feeding force just sufficient to overcome the recoil of the hammer piston disposed within the cylinder 6 and thereby hold the steel in spotting position at the working face. My improved balancing valve also must have embodied therein means for not only balancing the fluid pressure forces acting on the pressure areas of the feed piston, but also balancing the weight of the drilling mechanism when the same is disposed in an inclined position. More specifically, this valve comprises an enlarged central portion 31 disposed in a bore 32 and having outwardly projecting piston members 33 and 34 reciprocably mounted within bores 35 and 36 respectively. Said central portion has spaced annular grooves 37 and 38 communicating respectively with the bores 35 and 36 as by passages 39 and 40 in the valve 29, while passages 41 and 42 and small vent ports 41^a and 42^a allow communication between the bores 35 and

36 to the atmosphere depending upon the position of the valve 29. In the position of the valve 29 shown in Fig. 2, the bore 36 is vented through the port 41^a while if in its other extreme position, the bore 35 would be vented through the port 42^a. When the valve is in its forward position, live pressure fluid is admitted to the front of piston 23 as by a passage 43 leading from the main valve 10, an annular groove 44 formed on the periphery of the valve 30, a passage 45, groove 37, passage 39 to the bore 35, out a passage 46, an annular groove 47 also formed on the periphery of the valve 30, through a passage 48 and thence through tube 26 to the front side of the piston 23. When the pressure in bore 35 becomes great enough, due to the building up of pressure in the forward end of the feed cylinder, the valve 29 will be thrown in its other position, said bore being vented to atmosphere as by way of passages 39 and 42, while live fluid flowing from the passage 45 will pass around annular groove 38, passage 40, bore 36, a passage 49, around an annular groove 50 formed in the valve 30 intermediate the grooves 44 and 47, a passage 51 leading to the hollow bore of piston rod 21 and port 52 to the rear side of the piston 23. It will herein be noted that when the valve 29 is in a position opposite from that shown in Fig. 2 the bore of the cylinder at the front side of the piston is vented to atmosphere by way of passages 48 and 46, groove 37 in the valve 29, and exhaust passage 42. In order to allow free movement of the valve 29 both ends of bore 32 are vented to atmosphere as by the ports 41^a and 42^a communicating with the exhaust passages 41 and 42, respectively. This position of the valve 30 is maintained by the operator merely pressing the button 54 against the tension of a spring 55. It will be stated here that inasmuch as it is the purpose of the balancing valve 29 to maintain substantially equal forces on each side of the piston 23, the effective pressure areas on the ends of the pistons 33, 34 having the same proportion to the weight of this valve as the corresponding pressure areas on the feed piston 23 have to the weight of the tool actuating motor and the parts of the mechanism movable therewith.

In the operation of the device thus far described, if it is desired to "spot" the hole, the valve 30 will be pushed to the position shown in Fig. 2 in which case pressure fluid will flow from the control valve 10 through the passage 45 to the end of bore 35 and to the forward side of piston 23 and when the pressure on that side of the piston builds up, say to a pressure less than line pressure, this pressure acting upon the forward effective area of the piston 23 will throw valve 29 to its other position. Said bore 35 is then immediately vented to the atmosphere through groove 37 in the valve 29 and exhaust passage 42, but the passage 46 is of sufficient length to take a considerable time to wholly relieve the pressure in front of the piston 23 and, as will be presently seen, the valve 29 travels fast enough so that a substantially constant pressure will be maintained in the feed cylinder at all times. It will be understood that the relatively slight fluctuation of the valve 29, herein between the limits of $\frac{1}{16}$ th to $\frac{1}{8}$ th of an inch, has no material effect on the pressure in the feed cylinder. The valve 29 will now distribute fluid pressure to the passage 49 from the supply passage 45 through groove 38 and passage 40 in the valve and through the bore of the hollow piston rod 21 to the rear side of piston 23. The resistance to movement of the valve 29 in either direction is the same, consequently requiring the same throwing force. However, when the valve 29 is in the left hand position due to the effective area of the piston 34 being smaller than the effective area of the piston 33, it will be obvious that a greater pressure will have to be built up in the bore 36 than in the bore 35 in order to obtain equal throwing forces. The result is that the piston 29 will stay in its left hand position a sufficient length of time to allow pressure to be built up on the rear side of the piston 23 to substantially line pressure, which will then be transmitted to the piston 34 to throw the valve to its right hand position to repeat the cycle, the forward side of the feed piston being connected to exhaust by way of passage 39, groove 37 in the valve 29 and exhaust passage 42. Thus the pressure per square inch on the front and rear side of piston 23 will not be allowed to become equal due to the opposed differential pressure areas of the valve 29 and the difference of time required to throw the valve in opposite directions, but the total force on each side thereof will be substantially equal. If it is desired to feed the mechanism forward slightly or to hold the same slightly against a working face in which a hole is being spotted, the diameters of pistons 33 and 34 may be varied so as to obtain a slightly greater forward feeding force than reverse which will compensate for any recoil from the hammer piston which would ordinarily tend to push the tool away from the face. Having spotted the hole the push button 54 controlling the valve 30 is released by the operator, thus shutting off flow of live pressure fluid through the passage 45 to the annular groove 37 of the valve 29 and will also cut off passages 46 and 49 leading to the ends of pistons 33 and 34, thus wholly cutting out the operation of said balancing valve. When in its released position the valve 30 will still allow the passages 51 and 48 to be in communication with the main control valve 10 and consequently live with pressure fluid as by passages 56 and 57, communicating with the passages 48 and 51 respectively, through annular grooves 47 and 50 formed in the periph-

ery of the valve 30. The main control valve 10 also has ports (see Fig. 5) which will allow live fluid pressure to flow through only one of the passages 56 or 57 so that either a forward or reverse feed may be had.

It is thought that the operation of my device will be apparent from the foregoing description in connection with the balancing valve 29, but it is to be noted that by my improved balancing valve the operator needs only to press the button 54 whereby the feed for the drilling mechanism will be suitable for spotting conditions and does not require the operator to first throw the main control valve 10 in one direction to obtain a forward feed and then in the reverse direction to obtain a reverse feed in order to counteract the full forward feeding force. When the drill is in an inclined position there will be a tendency for the drill due to its weight to slide back or forward, depending upon the direction of inclination of the drill. This necessitates a greater pressure on the side of the piston, in which direction the mechanism tends to slide, to hold the drill in a balanced condition. This is accomplished by making the weight of the valve 29 in proportion to the weight of the movable part of the drilling mechanism. If the drill is inclined the pressure on the small area 34 necessary to move the valve 29 will automatically be increased for the valve will remain in its lower position until the pressure builds up in the feed cylinder. Of course during this operation the range of pressure at the ends of the valve 29 is such that line pressure is never attained thereby leaving an excess pressure to be used when the drill is inclined.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A drill mechanism comprising a tool actuating motor, feeding means therefor including relatively movable elements, means including a valve to subject one of said elements to opposing fluid pressure created forces for automatically maintaining said feeding means in a substantially balanced condition, said valve moving oppositely automatically in accordance with variations in said forces to control the supplies of fluid which produce said forces, and means including a valve operable at the will of the operator for controlling said automatic means.

2. A drill mechanism comprising a tool actuating motor, feeding means therefor including relatively movable elements, means including a valve to subject one of said ele-

ments to opposing fluid pressure created forces for automatically maintaining said feeding means in a substantially balanced condition to reduce the work performance thereof, said valve moving oppositely automatically in accordance with variations in said forces to control the supplies of fluid which produce said forces, and means including a valve operable to render said automatic means inoperative to allow said feeding means to normally operate.

3. A drill mechanism comprising a tool actuating motor, pressure fluid actuated feeding means therefor comprising a feed cylinder and a feed piston therein, said feed piston having differential pressure areas, and means including a valve responsive to pressure conditions within said feed cylinder and having pressure areas proportional to said differential piston areas for controlling the flow of fluid to said feed cylinder.

4. A drill mechanism comprising a tool actuating motor, pressure fluid actuated feeding means therefor comprising a feed cylinder and a feed piston therein, said feed piston having differential pressure areas, and means for controlling fluid flow to said cylinder including a valve responsive to pressure conditions in said cylinder, the pressure areas on said valve having the same proportion to the weight of said valve as the corresponding pressure areas on said piston have to the weight of said tool actuating motor and the parts of the mechanism movable therewith.

5. A drill mechanism comprising a tool actuating motor, pressure fluid actuated feeding means therefor comprising a feed cylinder and a feed piston therein, said piston having differential pressure areas, and means including a valve responsive to pressure conditions within said feed cylinder and having pressure areas proportional to said differential piston areas for controlling flow of fluid to said cylinder to automatically maintain substantially equal opposing forces thereon.

6. A drill mechanism comprising work performing means for actuating a drill steel, pressure fluid actuated forward and reverse feeding means therefor including a piston, and means comprising a directly fluid actuated valve operable independently of said piston and responsive to pressure changes in said feeding means for automatically maintaining said feeding means in a substantially balanced condition during "spotting" of a hole.

7. A drill mechanism comprising a motor for actuating a drill steel, pressure fluid actuated feeding means therefor including a feed piston having opposed differential pressure areas, and means comprising a valve responsive to pressure conditions in said feeding means and having opposed differential pressure areas proportional to the areas of said piston, said means being effective for

automatically maintaining said feeding means in a substantially balanced condition.

8. In a drill mechanism comprising work performing means, pressure fluid actuated feeding means therefor comprising a cylinder and a cooperating piston, and means independent of said piston and responsive to pressure changes in the ends of said cylinder at opposite sides of said piston for automatically maintaining said feeding means in a substantially balanced condition.

9. A drill mechanism comprising work performing means, pressure fluid actuated feeding means therefor comprising a feed cylinder and a cooperating feed piston, and means responsive to pressure changes in said cylinder for automatically alternately supplying pressure fluid to the opposite sides of said piston for maintaining said feeding means in a substantially balanced condition.

10. A drill mechanism comprising a motor for actuating a drill steel, pressure fluid actuated feeding means therefor including a piston, a main throttle valve for controlling

said motor and feeding means, means comprising a directly fluid actuated valve independent of said piston and responsive to pressure changes in said feeding means for automatically maintaining said feeding means in a substantially balanced condition, and manually operable valve means for controlling the fluid flow between said main valve and said automatic valve.

11. A drill mechanism comprising a motor for actuating a drill steel, pressure fluid actuated feeding means therefor including a piston, a main throttle valve for controlling said motor and feeding means, means comprising a directly fluid actuated valve independent of said piston and responsive to pressure changes in said feeding means for automatically maintaining said feeding means in a substantially balanced condition, and manually operable valve means to cut out said automatic means during normal feeding of the motor.

12. A drill mechanism comprising a motor, pressure fluid actuated feeding means therefor including a feed cylinder and a cooperating piston, the latter having differential pressure areas, and a valve responsive to pressure conditions in said feed cylinder and having pressure areas proportional to said differential areas for maintaining said feeding means in a substantially balanced condition.

13. A drill mechanism comprising a tool actuating motor, pressure fluid actuated feeding means therefor comprising a feed cylinder and a feed piston therein, said feed piston having differential pressure areas, and means for maintaining said feeding means in a substantially balanced condition including a valve responsive to pressure conditions in said cylinder, the pressure areas on said valve having the same proportion to the weight of said valve as the corresponding pressure areas on said piston have to the weight of said tool actuating motor and the parts of the mechanism movable therewith.

14. A drill mechanism comprising work performing means, pressure fluid actuated feeding means therefor comprising a cylinder and a cooperating piston, and means comprising a valve responsive to pressure changes in said feeding means for automatically alternately connecting the ends of said cylinder at opposite sides of said piston to supply and exhaust for maintaining said feeding means in a substantially balanced condition.

15. A drill mechanism comprising work performing means, pressure fluid actuated feeding means therefor including a piston, and means comprising a valve independent of said piston and having opposed differential pressure areas subjected to pressure changes in said feeding means for automatically maintaining said feeding means in a substantially balanced condition.

In testimony whereof I affix my signature.

THORE R. E. RUNDQVIST.
